UNITED STATES PATENT OFFICE.

WILLIAM H. THOMPSON, OF MORRISTOWN, NEW JERSEY, ASSIGNOR
OF ONE-HALF TO JOHN S. W. THOMPSON, OF MORRISTOWN, NEW
JERSEY.

FOLDING BOX.

SPECIFICATION forming part of Letters Patent No. 783,805, dated February 28, 1905.

Application filed June 10, 1903. Serial No. 160,823.

To all whom it may concern:

Be it known that I, WILLIAM H. THOMPSON, a citizen of the United States, residing at Morristown, county of Morris, and State of New Jersey, have invented certain new and useful improvements in Folding Boxes, fully described and represented in the following specification and the accompanying drawings, forming a part of the same.

This invention aims to provide an improved folding box, and especially to provide an improved lock for the folded ends or sides of such boxes.

By my invention a box is provided which is easily set up and knocked down, which is strong and rigid when set up, is of attractive appearance, having its exposed sides and ends unbroken and having no projecting parts on the inside liable to be engaged by articles packed in the box or to interfere with the use of the box, and the blank for which cuts to advantage without waste of material.

A full understanding of the invention can best be given by a detailed description of a preferred form of box embodying the various features of the invention, and such a description will now be given in connection with the accompanying drawings.

In said drawings, Figure 1 is a plan view of an unfolded blank cut and scored in accordance with the invention. Fig. 2 is a perspective view of the box set up. Fig. 3 is a broken perspective view of one end of the box partly set up.

Referring to the drawings, and first to Fig. 1, the blank, which may be formed of paper-board or other suitable sheet material, comprises a bottom section *a* and sides *b b* and *c c*, extending from the edges of the bottom section and separated therefrom by score-lines, as usual. Extending from the ends of the sides *b b* are end flaps *d d* and *e e*, and extending from the sides *c c* are flaps *f f*, adapted to fold inwardly and downwardly inside the box. For providing the box with a hinged cover formed in one piece with the body of the box, a cover-section *g* may be provided, extending from the outer or upper edge of one of the sides *b*, this cover-section being of a

size and form corresponding with the bottom 50 of the box and preferably being provided with edge tucks *h h* and *i*.

One of the flaps *d d* is cut to form an upwardly-pointing tongue *k*, the free end of which is near that edge of the flap which is at 55 the top when the box is set up, and this tongue does not extend entirely to said top edge of the flap, but the top portion of the flap is left uncut to form a connecting-strip *l* above the upper end of the tongue. The other flap *d* is 60 formed with an opening *m*, preferably corresponding to the size and position of the tongue *k*. This opening is preferably of the form shown corresponding to the form of the tongue *k*, so that when the end flaps *d d* are 65 brought together to form the end of the box, as shown in Fig. 3, the tongue *k* may be readily forced inward through the opening *m* and by projecting through said opening will securely lock the flaps *d d* together, and one 70 or both of the edges of the opening are preferably formed with slight inward projections or ears *m' m'*, which when the tongue *k* is pressed through the opening will snap back of the tongue, as shown in Fig. 3, and thereby 75 securely hold the inner flap *d* in position against the end of the box. Evidently projections might be formed on the side edges of the tongue to snap back of the edges of the opening. It will be understood, however, 80 that the opening *m* need not in all cases correspond to the form of the tongue *k*; but the lower portion of the opening should be of such a width or so positioned that when the tongue *k* is projected through the opening the 85 flaps *d d* will thereby be locked together. The opening *m* also preferably does not extend quite to the top edge of the flap *d*, but a connecting-piece *n* is left corresponding to the connecting-piece *l*. By forming the tongue 90 *k* and opening *m* so as to leave these connecting-strips *l m* the weakening of the flaps *d d*, which would result from extending the tongue and opening clear to the upper edge of the flaps, is avoided and a much more secure and 95 rigid box is secured. The flaps *e e* are similarly provided, one with a tongue *k* and the other with an opening *m*.

Each of the flaps *f* is formed with a slit *o*, extending preferably substantially horizontally and in position to receive the end of the tongue *k* when the box is set up, as shown in 5 Fig. 2.

To set the box up, the sides *b b* are turned upwardly and the flaps *d d* and the flaps *e e* are turned inwardly to overlap, as shown in 10 Fig. 3, the flap having the opening *m* being on the inside. The tongue *k* of the outer flap is then bent inward and projected through the opening *m*, as shown in Fig. 3, thereby 15 securely locking the overlapping end flaps together. The sides *c c* are then bent upwardly against the overlapping end flaps and the flaps *f f* turned over and downward inside the overlapping end flaps, and the ends of the inwardly-projecting tongues *k* are tucked inward through the slits *o* of the flaps *f*, as shown 20 in Fig. 2, thereby securely locking the sides *c* and the overlapping end flaps together and forming a secure fastening for holding the box rigidly in its set-up position.

Instead of providing the box with a folding 25 cover extending from the edge of one of the sides *b* the box, as shown in full lines, may be employed in connection with a similar part of slightly-larger size or with any suitable part for forming a telescope-box.

30 It will be understood that the invention is not to be limited to a box of the exact form or proportions shown, but that the construction shown may be varied as desired, according to the form and size of the box and the material of which it is made. While a single tongue *k* and opening *m* and slit *o* will generally be found sufficient for forming a secure lock, it will be understood that the invention is not to be limited to the use of a single 35 tongue, opening, and slit for locking up a side of the box.

What is claimed is—

1. A box having a wall formed of parts extending from adjacent walls, a tongue formed 45 in one of said parts, an opening in another of said parts through which said tongue is adapted to be bent flatwise and thereby lock said two parts together, and a locking-flap extending from another of said parts and adapted to 50 fold over and down against the parts having the tongue and the opening and inside the tongue, said flap having a slit through which the end of said tongue is adapted to be tucked inside the locking-flap, substantially as described.

2. A folding box having flaps extending from the ends of opposite sides and adapted to fold and overlap against a third side of the box, the one of said flaps lying next to said 60 third side of the box being formed with an upwardly-pointing tongue and the other of said flaps being formed with an opening through which said tongue may be bent flatwise, the lower portion of said opening being formed 65 to bear against said tongue for locking said

locking-flaps together, a flap extending upwardly from said third side of the box and adapted to turn over and downwardly against said flap having the opening and inside the tongue and formed with a substantially horizontal slit through which the upper end of said tongue is adapted to be tucked inside the locking-flap, substantially as described. 70

3. A folding box having flaps extending 75 from the ends of opposite sides and adapted to fold and overlap against a third side of the box, the one of said flaps lying next to said third side of the box being formed with an upwardly-pointing tongue and the other of said flaps being formed with an opening through 80 which said tongue may be bent flatwise, said flaps having uncut upper portions, a locking-flap extending upwardly from said third side of the box and adapted to turn over and downwardly against said flap having the opening and inside the tongue and formed with a substantially horizontal slit through which the upper end of said tongue is adapted to be tucked inside the locking-flap, substantially as described. 85

4. A folding box comprising a bottom portion, sides extending upward from the bottom portion, flaps extending from opposite edges of opposed sides and adapted to fold and overlap against the adjacent sides, one flap of each 90 pair being provided with an upwardly-pointing tongue and the other flap of each pair being formed with an opening through which said tongue may be bent flatwise, locking-flaps 95 extending from the tops of the last-mentioned sides adapted to turn over and downward against said overlapping flaps and inside the tongues and formed with a slit through which the upper ends of said tongues are adapted to be tucked inside the locking-flaps, substantially as described. 100

5. A folding box comprising a bottom portion and sides extending upward from the bottom portion, flaps extending from opposite edges of opposed sides and adapted to fold and overlap against the adjacent sides, one flap of each pair being formed with an upwardly-pointing tongue, and the other flap of each pair being formed with an opening through which the tongue may be bent flatwise, and said flaps 110 having uncut upper portions, and locking-flaps extending from the tops of the last-mentioned sides adapted to turn over and downward against said overlapping flaps and inside the tongues and formed with a slit through which the upper ends of said tongues are adapted to be tucked inside the locking-flaps, substantially as described. 115

6. A folding box comprising a bottom portion and sides extending upward from the bottom portion, flaps extending from opposite edges of opposed sides and adapted to fold and overlap against adjacent sides, one flap of each pair being formed with an upwardly-pointing tongue, and the other flap of each 120

pair being formed with an opening through which said tongue may be bent flatwise, and said flaps having uncut upper portions, locking-flaps extending from the tops of the last-mentioned sides adapted to turn over and downward against said overlapping flaps inside the tongues and formed with a slit through which the upper ends of said tongues are adapted to be tucked inside the locking-flaps,

- o and a cover extending from the top edge of one of said opposed sides having tucks *h h* and *i*, substantially as described.

7. A folding box having a wall formed of parts extending from adjacent walls, one of 5 said parts being formed with a tongue, another of said parts being formed with an opening through which said tongue is adapted to be bent flatwise and thereby lock said two parts together, the edge of the opening being o provided with a projection adapted to snap back of the tongue when the tongue is pressed through the opening, and a locking-flap ex-

tending from another of said parts and adapted to fold over and down against the parts having the tongue and the opening, said flap 25 having a slit for receiving the end of said tongue, substantially as described.

8. The combination of two parts of a folding box, one of said parts being formed with a tongue, another of said parts being formed with an opening through which said tongue is adapted to be bent flatwise and thereby lock said two parts together, side edges of said tongue and said opening being formed to snap one back of the other, substantially as de- 35 scribed.

In testimony whereof I have hereunto set my hand in the presence of two subscribing witnesses.

Correction in Letters Patent No. 783,805.

It is hereby certified that in Letters Patent No. 783,805, granted February 28, 1905, upon the application of William H. Thompson, of Morristown, New Jersey, for an improvement in "Folding Boxes," an error appears in the printed specification requiring correction, as follows: In line 66, page 2, the word "locking" and the hyphen before the word "flaps" should be stricken out, and the word *locking* should be inserted before the word "flap" in said line; and that the said Letters Patent should be read with this correction therein that the same may conform to the record of the case in the Patent Office.

Signed and sealed this 17th day of October, A. D., 1905.

pair being formed with an opening through which said tongue may be bent flatwise, and said flaps having uncut upper portions, locking-flaps extending from the tops of the last-mentioned sides adapted to turn over and downward against said overlapping flaps inside the tongues and formed with a slit through which the upper ends of said tongues are adapted to be tucked inside the locking-flaps,

- o and a cover extending from the top edge of one of said opposed sides having tucks *h h* and *i*, substantially as described.

7. A folding box having a wall formed of parts extending from adjacent walls, one of 5 said parts being formed with a tongue, another of said parts being formed with an opening through which said tongue is adapted to be bent flatwise and thereby lock said two parts together, the edge of the opening being o provided with a projection adapted to snap back of the tongue when the tongue is pressed through the opening, and a locking-flap ex-

tending from another of said parts and adapted to fold over and down against the parts having the tongue and the opening, said flap 25 having a slit for receiving the end of said tongue, substantially as described.

8. The combination of two parts of a folding box, one of said parts being formed with a tongue, another of said parts being formed with an opening through which said tongue is adapted to be bent flatwise and thereby lock said two parts together, side edges of said tongue and said opening being formed to snap one back of the other, substantially as de- 35 scribed.
